UNITED STATES PATENT OFFICE.

GARRY J. DORMANDY, OF TROY, NEW YORK, ASSIGNOR TO LION COLLARS & SHIRTS, INC., OF TROY, NEW YORK, A CORPORATION OF NEW YORK.

COLLAR AND METHOD OF MAKING SAME.

Original application filed December 9, 1921, Serial No. 521,151. Divided and this application filed December 19, 1924. Serial No. 756,868.

My invention more particularly relates to the manufacture of collars of that character or type known as turn-over collars.

My present application is a division of 5 my application Serial No. 521,151 which was filed in the Patent Office on December 9, 1921, and which matured into Patent No. 1,526,324 February 17, 1925.

My invention will best be understood by 10 reference to the accompanying drawings in which I have illustrated certain embodiments of my invention and in which Fig. 1 is a plan view of an extended collar embodying my invention, and looking at the 15 inside of the neck-band portion and of the turn-over portion; that is, the sides thereof that are folded into juxtaposition; Fig. 2 is a section taken on the line 2—2 of Fig. 1; Fig. 3 is a section taken on the line 3—3 20 of Fig. 1 and Fig. 4 is a view similar to Fig. 2 illustrating in section a modified form of my invention.

Like reference characters indicate like 25 parts throughout the drawings.

Referring now to the drawings, 1 designates a neck-band member of any suitable 30 design provided with end tabs 2, having buttonholes 3, adapted to be engaged with a stud or button at the front of the neck-band of a shirt upon which the collar is to be worn, said neck-band member also being provided at its central or rear portion with a buttonhole 4, adapted to be engaged with a stud or button at the rear of the neck-band of a shirt. The collar also comprises 35 a fold-over or turn-over portion or member 5, the neck-band member and the turn-over member, in the form illustrated, being made of separate pieces of material. The turn-over member 5 may be of any suitable design 40 or style, without departing from the scope of my invention. In order to provide a proper fold between the neck-band member and turn-over member, so that the collar will 45 properly fold at the fold line and maintain the desired shape and position when worn, I provide a novel seam or fold between the said neck-band and turn-over members. The upper edge portions of the collar members, that is, of the neck-band member and 50 of the turn-over member, are cut to give the collar the desired configuration when folded and in position on the neck of the wearer; that is, they are cut preferably upon a curve.

For this purpose, the upper edge of the neck-band member is cut on a convex curve and the adjoining or upper edge of the turn-over member on a concave curve to conform thereto. The turn-over member and the neck-band member are then laid with 55 the outer face of the turn-over member against the inner face of the neck-band member and the curved edges fastened together in alinement. This fastening may comprise a line of stitches 33, or a tape binding 34 60 lapped around the raw edges of the collar members and fastened by a lengthwise line of stitches 36; or, as shown, both the stitches 33 and binding 34 may be applied to fasten the collar members together. The turn-over 65 member may then be folded over into position to be worn, whereupon it will be seen that a seam or fold member is provided in the space between the turn-over and neck-band members, this fold or seam comprising 70 edge portions 36 of the said collar members, and the binding 34 enveloping said parts 36 75 (see Fig. 2).

The collar illustrated and above described may be made of any suitable fabric, 80 for example, any of the materials commonly employed in the manufacture of soft turn-over collars, such as heavy linen, duck, percale and multi-ply fabrics. In making the collar of such material, it may be desirable 85 to provide the same with suitable edge binding or finishing, which may be of any suitable form without departing from the spirit and scope of my invention, but, in one form, I employ binding, which I will 90 now describe.

In the form illustrated, the binding along the lower edge of the neck-band member may consist of a strip or tape 10 overlying the edge, and having its edge portions on the 95 opposite faces of the neck-band member and secured thereto by a longitudinal line of stitches 11. The binding for the lower longitudinal edge of the turn-over member may consist of a strip or tape 12 applied to the 100 lower edge of the fabric of the turn-over portion and arranged on opposite sides of the latter, as shown at 13, the parts 13 being, first, stitched to the edge 5^a of the member 5 by a line of stitches 14, whereupon the 105 edge portion 5^a is turned over upon the inner face of the turn-over member and secured thereto by one or more lines of stitches

15. The stitches 15, it will be seen, pass through all the layers of fabric, both of the turn-over portion and the said binding, and preferably extend lengthwise of the collar 5 throughout the length thereof. The end tabs 2 extend beyond the front edges 5^b of the turn-over member, and these tabs, as well as said edges, are also provided with a suitable binding, as best illustrated in Fig. 10 1. This binding consists of a piece of suitable fabric, for example, muslin, including a portion 16, which lies over the outer face of the buttonhole tap and a portion of the neck-band member, as clearly shown in full lines 15 in Fig. 1, said portion 16 being provided with a narrow extension 17, which forms the binding for the edge 5^b of the turn-over member. This binding is applied by first laying the same against the outer face of the neck-band and stitching the same thereto by a line of stitches 18 (see Fig. 3) extending lengthwise of the edge 5^b and the end edge of the buttonhole tab 2. The binding is then reversed and its free end folded over 20 upon the opposite face of the edge of the turn-over member and the tab, and the edge of the turn-over member carrying the binding so arranged is then folded over on a line 20 so that the edge portion 5^b thereof 25 lies parallel to the main portion of the collar on the end face thereof, whereupon lines of stitches 22 are run through the neck-band and turn-over portions lengthwise of the edge, thereby securing the binding portion down upon the underside of the turn-over member and the outer face of the neck-band member. A line of stitches 23 may then 30 be run lengthwise of the rear edge of the part 16 to secure said edge of the neck-band member and, if desired, this line of stitches 23 may extend through the binding at the edge 35 of the turn-over member (see Fig. 1), although this is not necessary. In the preferred form, the lower binding 10 is preferably arranged so as to overlie the lower edge of the part 16, as indicated at 16^a, and the line of stitches 11 utilized not only to hold the binding 10 in place, but also to hold the lower edge of the part 16. The part 40 16 is preferably so formed that its rear edge 16^b extends far enough inward on the neck-band so as to be covered by the turn-over member when the collar is worn. It will be seen that the turn-over member is provided with a binding which is not visible 45 when the collar is worn, and the buttonhole tabs are provided with a reinforcement which, although on the outside of the neck-band, is slightly and does not detract from 50 the appearance thereof. It will also be seen

that by the construction shown and described, I am able to form the end binding for the neck-band member, and the reinforcement for the buttonhole tab, of an integral piece, whereby the complications of manufacture 65 are simplified. The buttonholes 3 extend through the neck-band and the reinforcements 16, and the stitching for the buttonholes extends through said reinforcements. 70

In Fig. 4, I have illustrated a modified form of my invention in which the collar members, which are also formed of separate pieces of fabric, are joined by providing the neck-band member with an inturned fold 37 and the turn-over member with an inturned 75 part 38, the lower edge of which is reversed upon itself, as at 39, to receive and envelop the part 37. In this case, the parts 37 and 38 are connected by a line of stitches 40, corresponding to the line of stitches 33, 80 shown in Fig. 2, and I also preferably employ a line of stitches 41 extending through the edge portions of the parts 38 and 37 and the part 39 which encloses the part 37. 85

I claim:

1. A fold-over collar having principal parts for band and top respectively each formed of a single piece of single ply fabric, said parts having edges of similar but opposite curvature, the margins at said edges being united in face-to-face juxtaposition by a binding surrounding the said edges and fastened through said margins on a line parallel to said edges. 90

2. A collar comprising a band member and a turn-over member made of separate pieces of single ply fabric, each of said pieces having a fold located between the said members and the folds being stitched together at the fold line of the collar, and a tape binding overlying the fold edges of the band member and turn-over member and secured to said fold edges by a line of stitches extending lengthwise of the collar. 100

3. A fold-over collar comprising a band member and a turn-over member each having, in the folded position of the collar, in-turned edges lying face-to-face, and a fabric lapped around the in-turned facing edges of the collar members and secured to the said 105 in-turned edges.

4. A fold-over collar comprising a band member and a turn-over member each having, in the folded position of the collar, in-turned edges lying face-to-face, and a tape 110 lapped around the in-turned facing edges of the collar members and secured to the said in-turned edges.

GARRY J. DORMANDY.
